Primary Examiner — Calvin E Vansant*Assistant Examiner* — Mark T. Philipp(74) *Attorney, Agent, or Firm* — Bay State IP, LLC(57) **CLAIM**

The ornamental design for a wood chipper, as shown and described.

DESCRIPTION

FIG. 1 is a front perspective view of a wood chipper showing my new design;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

The broken lines shown in the drawings depict portions of the design that form no part of the claimed design.

1 Claim, 7 Drawing Sheets(56)
